STIFFENED CLOTH

Hermine Goldberg, Omaha, Nebr., assignor of
one-half to Ralph D. Goldberg, Omaha, Nebr.

Application March 13, 1948, Serial No. 14,689

2 Claims. (Cl. 28—79)

1

This invention relates to a stiffened cloth, that is one which is used as an insert in belts, brassières, shoulder pads, collars, etc., the general character of the stiffened cloth being such as to provide one which retains its stiffness in spite of repeated wearing, laundering and cleaning and at the same time is soft and pliable, thus making it comfortable to wear and natural to behold.

One object of this invention is to provide a stiffened cloth which, when incorporated in a brassière or belt, etc., has sufficient stiffness to be comparable with belting, crinoline, canvas, boned materials and wired ones without the disadvantages of these materials, the rigidly stiff ones being uncomfortable to wear and unnatural to look at, those like canvas, crinoline, etc. which depend for their stiffness on starch and glue sizing, becoming limp when worn, laundered or dry cleaned because the starch and glue sizing comes out. Boning prevents the body from bending and wires such as are used in brassières must generally be removed when laundering and many health authorities claim that the pressure from the wires is detrimental to health.

This stiffening material consists of a suitable, flexible base such as one or more layers of ordinary felt cloth, stiffening being accomplished by ordinary sewing machine stitching in rows, in one direction of the felt, but preferably lengthwise of the cloth and crosswise of the cloth. The closer the stitching, the stiffer the cloth becomes. Felt cloth is in itself relatively soft and flexible and has some stiffness too. It consists of wool or other fibres matted together by means of pressure and rolling, but when felt is laundered or dry cleaned, it wads up and shrinks, and any pressure on it will stretch it out of shape since it is just matted fibres. However, when felt is stitched as just described, the fibres cannot pull apart and when laundered or dry cleaned, the felt does not wad or shrink or get stretched out of shape, also the stitching stiffens the felt, the closer the stitching, the stiffer the finished cloth and yet it still retains its soft and pliable character which makes it comfortable to wear and more natural to behold. Therefore, it makes a very desirable stiffening base for brassières, belts, shoulder pads, collars, etc.

With these and other objects in view, my in-

2

vention consists of a stiffened cloth of the kind disclosed, whereby the objects contemplated are attained as hereinafter more fully set forth, pointed out in my claims and illustrated in the accompanying drawings, wherein:

Figure 1 illustrates a piece of ordinary felt cloth.

Figure 2 illustrates the same cloth (with the stippling of Figure 1 omitted for greater clarity) 10 stitched longitudinally.

Figure 3 illustrates the cloth stitched laterally, this figure, for clarity, omitting the longitudinal stitching that was performed in Figure 2.

Figure 4 is an enlarged swatch of the cloth 15 showing both the longitudinal and lateral stitching accomplished by the sewing operations illustrated in Figures 2 and 3.

Figure 5 is a perspective view of a skirt having a belt with a portion of the belt broken away 20 and showing my stiffened cloth included therein as an insert.

Figure 6 shows two layers of felt stitched together to make an extra heavy piece of stiffening cloth to be used when ordinary stiffness is not 25 sufficient.

Figure 7 is a pattern cut from the stiffened cloth, the cloth then being used to form the brassière base.

Figure 8 is a perspective view of a brassière base 30 made from the pattern of Figure 7, and

Figure 9 is a perspective view of a shoulder pad, using my stiffened cloth as an insert therein.

On the accompanying drawing I have used the 35 reference numeral 10 to indicate a piece of cloth, preferably felt. Felt is a cloth that is formed by "felting" wool or similar fibres together by means of pressure and usually by a rolling action, wherein the fibres are passed between rolls which exert the necessary pressure for felting or compacting the fibres together so that they are retained in that condition as a cloth during normal handling operations. Felt alone, however, will not stand laundering as the 40 fibres pull apart thus wadding and shrinking and the pressure of a finger can stretch the cloth. In other words, felt cannot be depended upon to maintain its original shape when laundered or dry cleaned unless it is stitched as I have previously outlined.

In Figure 2, I illustrate one step in my stiffening operation for the cloth 10 which consists of longitudinal stitching 12. This may be done on an ordinary sewing machine, the stitching being relatively close together as illustrated in the full size swatch of Figure 4. The stitching need not necessarily be uniform and it can accordingly be done on an ordinary sewing machine. In factory production, however, the best method is probably a row of sewing machine heads, each one sewing a row of stitching and the rows being as close as $\frac{1}{2}$ or $\frac{1}{4}$ of an inch apart.

After the longitudinal stitch, I stitch the cloth laterally as at 14 and here again the stitching may be done uniformly with a plurality of sewing machine heads or in an irregular manner as would be the result of guiding the cloth by hand in relation to a single sewing machine head. In that event, the stitching could zig-zag longitudinally and laterally across the cloth 10, turning the cloth around at the ends and sides as is obvious from the sewing patterns illustrated in Figures 2 and 3.

The final stiffened cloth with both longitudinal and lateral stitching may then be cut to a desired pattern. For instance, a long strip indicated at 10a on Figure 5 may be cut to serve as the stiffening for the belt of a skirt 16. In any event, the felt cloth 10, stiffened by the stitching 12 and 14 provides an insert which gives the necessary stiffness to prevent wrinkling down of the belt when worn.

The stiffening strip 10a may be stitched in the belt by means of several rows of machine stitches if desired. Belts with inserts of stiffening material such as belting, crinoline, canvas, etc. depend on starch and glue sizing for their stiffness and when worn, laundered or dry cleaned, the starch or glue comes out and the belt becomes limp and wrinkles down into a string around the waist. This is both unsightly and uncomfortable to wear. Also the stitched felt stiffening material has another advantage over the starch and glue sizing type of stiffening because it is soft and flexible and at the same time retains its stiffness even when laundered or dry cleaned while they have a stiffness which resembles paper and after use, they lose their sizing and become limp. The stitching, as stated before, prevents wadding and shrinking or stretching of the felt and also makes the felt stiffer according to the amount of stitching done on it—the closer the stitching, the stiffer the finished piece.

Stiffening cloth of the character disclosed is very adaptable for brassière construction, particularly the so-called "uplift" brassières and "strapless" brassières as these require considerable stiffness of the cloth for the "up-lift." The rigidly stiff materials used are very uncomfortable to wear and unnatural to behold and very often do not retain their original stiffness with laundering and dry cleaning. Those using stiffening which depend on starch and glue sizings become limp when the sizing is gone and it disappears with wear, laundering and cleaning. This type of material is also uncomfortable to wear because it has paper stiffness at first and nothing at all after laundering or cleaning. The soft types depend on shoulder straps pulled up very tightly—to produce the "uplift" and these cut into the shoulders and are extremely uncomfortable to wear and when boned, they prevent the wearer from bending over in comfort. The brassières with wire construction are unsatisfactory because as a rule the wires must be removed when launder-

ing and then replaced. Besides many health authorities believe that the pressure of the wires is unhealthy.

Using stitched felt as disclosed, however, even an entirely strapless model brassière can be made without benefit of wires or boning. At the same time, the stitched felt has a resilience and softness which is comfortable to wear and natural to behold and it retains its stiffness and original shape, no matter how many times laundered or dry cleaned. Also it does not need ironing after it is washed.

One thickness of felt, stitched very closely, is sufficiently stiff for the normal breast, but if more stiffness is needed, two layers of felt are stitched together instead of the one.

In Figure 6, I have shown how two thicknesses of material may be stitched together to provide greater stiffness as referred to in the last paragraph. These two thicknesses may be both felt or one may be felt and the other a woven cloth indicated at 26 in which the weave serves as a further reinforcement for the felt. Such cloth of course need have no stiffening material in it as when it is stitched to the felt by means of the stitching 12 and/or 14. The desired stiffness is secured in the manner already set forth.

In Figure 7, I have illustrated a pattern 10b from which a suitable brassière base may be formed. The pattern, it will be noted, is merely cut from a section of the stiffened cloth, has a circular shape and is provided with a V notch, the sides of which, when secured together as by means of stitching 20, form a substantial cone-shaped base as illustrated in Figure 8.

Stiffened cloth of the character disclosed is also suitable as a base for shoulder pads 22 as illustrated in Figure 9. The base is indicated at 10c and forms the liner for the shoulder extension pads, or the stiffened cloth is merely covered on both sides and the assembly secured together as by stitching illustrated at 24.

In addition to the stitch-stiffened felt, lamb's wool or the like may be steamed and compressed into shape on a mold to serve as an additional insert with the stiffened cloth 10c in the shoulder pad. This, of course, in case it is desirable to have the pad built up to greater thickness than one or a plurality of thicknesses of felt cloth or built up to some desirable shape to fill out the shoulders of the wearer in a desirable manner. A shoulder pad of this character is relatively light and comfortable to wear. The stiffened cloth herein disclosed is relatively inexpensive to manufacture, yet fulfills the necessity for a stiffened but flexible base for belts, brassières, collars and in fact wherever stiffening is needed. The possibility of repeated launderings highly recommends the use of a material of this type as well as the fact that truly comfortable wearing can be achieved by its use.

Some changes are possible without departing from the real spirit and purpose of my invention and it is my intention to cover by my claims any modified forms of structure or use of mechanical equivalents which may be reasonably included within their scope.

I claim as my invention:

1. A stiffened material for belts, brassières, shoulder pads and collars consisting of a fabric of felted wool fibers provided with rows of stitching extending across the fabric substantially at right angles with respect to each other, said rows of stitching being spaced closely so that adjacent rows of stitches engage the same fibers of the

fabric to prevent breakdown of the fibers of the fabric when said stiffened material is laundered.

2. A stiffened material for belts, brassières, shoulder pads and collars consisting of a fabric of felted wool fibers provided with rows of sewing machine stitching extending both longitudinally and laterally across the cloth, said rows being spaced closely so that adjacent rows of stitches engage the same fibers of fabrics to prevent breakdown of the fibers of the fabric when said stiffened material is laundered.

HERMINE GOLDBERG.
